UNITED STATES PATENT OFFICE.

REUBEN D. MORGAN, OF CLEVELAND, OHIO.

FOLDING STOOL.

1,075,591.

Specification of Letters Patent. Patented Oct. 14, 1913.

Application filed November 4, 1911. Serial No. 658,471.

To all whom it may concern:

Be it known that I, REUBEN D. MORGAN, a citizen of the United States of America, residing at Cleveland, in the county of Cuyahoga and State of Ohio, have invented certain new and useful Improvements in Folding Stools; and I hereby declare the following to be a full, clear, and exact description of the invention, such as will enable others skilled in the art to which it pertains to make and use the same.

This invention relates to improvements in folding stools, and pertains more especially to a folding stool comprising leg-frames and seat-frames relatively arranged to render them capable of being folded together and nested when the stool is not in use.

The primary object of this invention is to effect the reduction, to a minimum, of the space occupied by the stool when the component parts of the stool are folded together.

Another object is to render the stool simple and durable in construction.

With these objects in view, this invention consists in certain structural features, and combinations and arrangement of parts, hereinafter described, pointed out in the claims, and illustrated in the accompanying drawings.

In said drawings, Figure 1 is an elevation of a folding stool embodying my invention. A portion of the tie-bar E shown in Fig. 1 is broken away to show the recess 15 in the adjacent leg-frame. Fig. 2 is a right-hand side view relative to Fig. 1. Fig. 3 is a horizontal section on line 3—3, Fig. 1, looking downwardly. Fig. 4 is a horizontal section on line 4—4, Fig. 1, looking downwardly. Figs. 5 and 6 are views showing the component parts of the stool folded together. Fig. 7 is a section on line 7—7, Fig. 1, looking outwardly. Fig. 8 is a section on line 8—8, Fig. 1, looking inwardly.

My improved folding stool comprises a rod A which is arranged substantially horizontally and centrally of the stool.

B indicates two U-shaped leg-frames which (see Fig. 1) diverge downwardly from the rod A. Each leg-frame B consists of a U-shaped metal bar and has its end-members rotatably mounted on and sup-

porting the rod A. One leg-frame is smaller in dimensions externally than the other leg-frame is internally and arranged between the end-members of the larger leg-frame to permit swinging of the smaller leg-frame inside of the larger leg-frame upon swinging the leg-frames laterally outwardly and upwardly in folding the component parts of the stool together as shown in Figs. 5 and 6. The smaller leg-frame is preferably enough shorter than the larger leg-frame to effect the formation, for the purpose hereinafter appearing, of a suitable space 10, Fig. 6, between the central members of the two leg-frames when the component parts of the stool are folded together, as shown in Figs. 5 and 6.

C represents two inverted U-shaped seat-frames which (see Fig. 1) diverge upwardly from the rod A. Each seat-frame C consists of an inverted-U-shaped metal bar and has its end-members rotatably mounted on the rod A. Both seat-frames are smaller in dimensions externally than the smaller leg-frame is internally and arranged between the end-members of said leg-frame to permit swinging of the seat-frames inside of said leg-frame in folding the component parts of the stool together, as shown in Figs. 5 and 6. One seat-frame is smaller in dimensions externally than the other seat-frame is internally and arranged between the end-members of the larger seat-frame to permit the swinging of the smaller seat-frame inside of the larger seat-frame in folding the component parts of the stool together, as shown in Figs. 5 and 6.

The larger seat-frame is preferably enough shorter than the smaller leg-frame to effect the formation, for the purpose hereinafter appearing, of a suitable space 12, Fig. 6, between the central member of said leg-frame and the central member of 95 said seat-frame when the component parts of the stool are folded together as shown in Figs. 5 and 6.

The smaller seat-frame is preferably enough shorter than the larger seat-frame to effect the formation, for the purpose hereinafter appearing, of a suitable space 13, Fig. 6, between the central members of the two seat-frames when the component

parts of the stool are folded together as shown in Figs. 5 and 6.

A seat D of flexible material, such, for instance, as canvas, extends (see Fig. 1) between and is suitably attached to the central members of the seat-frames.

Each end-member of the smaller leg-frame is provided, in its outer longitudinal edge and a suitable distance below the rod 10 A (see Figs. 1 and 4) with a recess 15 extending from side to side of said end member, as shown in Fig. 6, and a tie-bar E is arranged at the outer side of said end-members of said leg-frame and provided with a 15 projecting member e which (see Figs. 1 and 4) engages said recess and has a shoulder 16 overlapping the inner side of said end-member of said leg-frame, which tie-bar extends to and overlaps the outer side of the 20 adjacent end-member of the larger leg-frame and is pivoted, as at 17, to said end-member of the larger leg-frame substantially parallel with the rod A. Obviously the 25 tie-bars E are instrumental in preventing lateral outward movement of the leg-frames.

At each side of and spaced from the rod A is a folding tie-frame which extends between the seat-frame and leg-frame which 30 projects laterally of said side of said rod, and said tie-frame is connected to said leg-frame and to said seat-frame and comprises an upper substantially V-shaped link G and a lower substantially inverted V-shaped link 35 H. Said links intersect at their adjacent portions, and preferably the upper portion of the lower link H is in the form of a loop h through which the lower portion of the upper link extends. Preferably each link 40 of each tie-frame (see Figs. 1, 7 and 8) terminates in pivotal members 18 which are substantially parallel with the rod A and arranged in line endwise.

The lower link H of each tie-frame extends between the end-members of the leg-frame to which said tie-frame is connected and has its pivotal members 18 journaled in said end-members of said leg-frame in proximity to the central member of said 50 leg-frame, and said link H is offset laterally and inwardly, as at 20, (see Figs. 1 and 4) at the inner ends of said pivotal members.

The upper link G of each tie-frame extends between the end-members of the seat-frame to which said tie-frame is connected and has its pivotal members 18 journaled in said end-members of said seat-frame in proximity to the central member of said seat-frame, and said link is offset laterally 55 and outwardly, as at 22, (see Figs. 1 and 7) at the inner ends of said pivotal members.

By the construction hereinbefore described it will be observed that the tie-bars E, upon manipulating the leg-frames to disengage 60 the projecting members e of said tie-bars

from the engaging recesses 15, are rendered free to be swung toward the leg-frame to which said tie-bars are pivoted, and said tie-bars possess enough springiness to permit of bringing them at their projecting members e 70 into position at the outer sides of the end-members of said leg-frame, as shown in Fig. 6, and obviously when said tie-bars have been swung into the position shown in Fig. 6 the seat-frames, the leg-frames, the seat and the tie-bars are free to be folded together as shown in Figs. 5 and 6.

Not unimportant are the offsets 20 and 22 of the links G and H of the tie-frames and the relative arrangement and sizes of the seat-frames and leg-frames as hereinbefore described to form the spaces 10, 12 and 13, shown in Fig. 6, so as to permit of the nesting of the seat-frames and leg-frames and thereby effect the reduction to a minimum of the space occupied by the stool when the component parts of the stool are folded together as illustrated in Figs. 5 and 6.

What I claim is:—

1. In a folding stool, the combination 90 with a rod, of two inverted U-shaped seat-frames having the lower ends of their side members rotatably mounted on said rod, one of said seat frames being slightly smaller than the other and adapted to telescope 95 within the larger one, a flexible seat extending between and attached to said seat frames, two U-shaped leg frames having the upper ends of their side members rotatably mounted on said rod, one of said leg frames being smaller than the other leg frame, but larger than the larger seat frame and adapted to telescope into the larger leg frame and over the larger seat frame when the 100 said frames are rotated toward each other, means for securing the leg frames together 105 to hold them at the proper angle for supporting the stool and means for locking the seat frames to said leg frames, for the purpose set forth.

2. In a folding stool, the combination of a rod, two inverted U-shaped seat frames having the lower ends of their side members rotatably mounted on said rod, one of said seat frames being smaller than the other seat frame and adapted to telescope into the larger seat frame, when said frames are rotated on said rod toward each other, two U-shaped leg frames having the upper ends of their side members rotatably mounted on said rod, one of said leg frames being smaller than the other leg frame and adapted to telescope into the larger leg frame when said leg frames are rotated on said rod, said seat frames and said leg frames 110 having such relative proportion that the seat frames when telescoped can in turn telescope 115 within the telescoped leg frames, a flexible seat extending between and attached to said seat frames, means for locking the seat 120 frames, and means for supporting the stool 125 when the seat frames are rotated toward each other, 130

frames to the leg frames and means for securing the leg frames together, said means comprising a bar pivotally secured to one of said leg frames, the other leg frame being provided with a notch in the outer edge thereof and said bar having a pin adapted to fit into the said socket.

In testimony whereof, I sign the foregoing specification, in the presence of two witnesses.

REUBEN D. MORGAN.
